UNITED STATES PATENT OFFICE.

CALVIN G. HAMPTON, OF RYDE STATION, CALIFORNIA.

AUTO STEAM-PLOW.

No. 873,229.

Specification of Letters Patent.

Patented Dec. 10, 1907.

Application filed February 28, 1907. Serial No. 359,876.

To all whom it may concern:

Be it known that I, CALVIN G. HAMPTON, a citizen of the United States, residing at Ryde Station, in the county of Sacramento, State of California, have invented certain new and useful Improvements in Auto Steam-Plows; and I do declare the following to be a full, clear, and exact description of the same, such as will enable others skilled in the art to which it appertains to make and use the same, reference being had to the accompanying drawings, and to the characters of reference marked thereon, which form a part of this specification.

15 This invention relates to improvements in plows and particularly to an auto-steam plow, my object being to produce a rotary plow operated by direct connection with the driving power, which power may be either 20 steam or gas or similar engines, as will appear. Also to produce a plow which will aid in driving itself forward. This object I accomplish by means of a spiral flanged plow share operated on the rotary principle; means 25 connecting said plow directly with the motive power and means for the regulation of the position of said plow; also by such other and further construction and arrangement of parts as will appear by a perusal of the following specification and claims.

In the drawings similar characters of reference indicate corresponding parts in the several views.

Figure 1 is a side elevation of the plow in full and showing likewise a fragmentary view of the propelling machine. Fig. 2 is a top plan view of Fig. 1.

1 Figure 1 designates the driving engine which may be either a steam traction engine, a motor engine or any other suitable driving power. Arranged in the rear of said motive means is a main frame 2 having side bars and a rear guide wheel 3, the same being disposed at an angle off from perpendicular for the purpose 45 of compensating any side draft of the machine. Said wheel is in connection with a steering shaft 4, said shaft 4 having a pulley 5 secured to the top thereof around which a chain 6 operates said chain extending over a pulley 7 thence under a pulley 8 and then to the steering shaft 9 of the motive power.

50 Pivotedly secured to the driving shaft 10 of the motive means are levers 11, one on each side, the rear ends of said levers being connected by pivoted links 11' to arms 12 secured to a rod 13 journaled in the rear of

the frame 2 secured to which rod 13 is a lever 14 operating in connection with a lever rack 15.

Pivotedly mounted about the center of the 60 levers 11 is a plow frame 16 carrying a shaft 17 formed with three plow shares or blades 18, the same being spiral shaped flanges, extending longitudinally with respect to said shaft 17, all of said flanges taken collectively 65 forming substantially an auger shaped plow share as shown in the drawings.

Journalized on the frame 2 just in front of the plow is a shaft 19 which is connected with the driving shaft 10 of the motive power by 70 means of suitable gears and chains 20. Said shaft 19 is also connected with the shaft 17 by means of gearing and a chain 21, all of said 75 gearings being so disposed as to rotate the plow at a greater speed than the driving wheel of the motive means.

In using the device the motive power is set in operation. This pulls the whole device forward, the chain and gear connections described causing the plow to rotate at a 80 greater speed than the driving wheels of the motive power, thus plowing the soil and at the same time pulling or aiding the said motive power to perform its functions by giving traction power thereto. This is a large 85 advantage over other power propelled plows for the reason that most plows pull back on and form a resistance to the motive power, while mine helps drive said motive power forward.

This enables my plow to operate in sandy or 90 soft land where an engine's drive wheels would slip or slide with an ordinary plow and thus fail to pull said plow. The wheel 3 is steered by the main steering wheel 22 by means of the specified chain and pulley connections, thus aiding in steering the device by one controlling means. When it is desired to raise the plow from contact with the soil the lever 14 is operated thus causing the rod 13 operating the arms 12 and links 11' to 95 pull the levers 11 upward, thus lifting the frame 16 upward and thus pulling the plow from the soil. The whole weight of said plow and the frame 16 is then supported by 100 the levers 11 which in turn are supported by 105 the main machine frame 2 as described, and the shaft 10.

Thus it will be seen from the foregoing specification that I have fulfilled all the objects of the invention as set forth therein.

110 While in this specification I have set forth the present and preferred detail of construc-

tion of my improved plow still in practice many small deviations therefrom may be resorted to without departing from the spirit of the invention.

5 Having thus described my invention what I claim as new and useful and desire to secure by Letters Patent is:—

10. 1. In a device of the kind described a motive means, side levers pivotally secured at their front ends to said motive means, a plow frame carrying a rear guide wheel, pivoted links connecting the rear ends of said levers to the integral arms of a rod journaled on said frame, a lever secured to said 15 rod and co-acting with a lever rack secured to said frame, a three bladed rotary spiral plow carried by said levers, said plow being connected to said motive means by suitable gearing, as set forth.
20. 2. In a device of the kind described a

frame movably secured to a motive means, a spiral three bladed rotary plow journaled upon a shaft and hung in adjustable connection with said motive means, a shaft journaled across the front end of said frame, 25 gear wheels on said plow shaft and said last named shaft, a chain connecting the two, two other gear wheels on said last named shaft, chains connecting said last named gears to the driving shaft of the motive means, to revolve said plow at a greater speed than that of the motive means and means for raising and lowering said plow, as set forth.

In testimony whereof I affix my signature 35 in presence of two witnesses.

CALVIN G. HAMPTON.
